(57) **CLAIM**

The ornamental design for a packaging bottle, as shown and described.

DESCRIPTION

FIG. 1 is a front view of a packaging bottle showing our new design;

FIG. 2 is a top view thereof;

FIG. 3 is a rear view thereof;

FIG. 4 is a bottom view thereof;

FIG. 5 is a left-side view thereof;

FIG. 6 is a right-side view thereof;

FIG. 7 is a cross-sectional view thereof taken along line 7—7 of FIG. 2;

FIG. 8 is a cross-sectional view thereof taken along line 8—8 of FIG. 2;

FIG. 9 is a cross-sectional view thereof taken along line 9—9 of FIG. 1;

FIG. 10 is a cross-sectional view thereof taken along line 10—10 of FIG. 1; and,

FIG. 11 is a cross-sectional view thereof taken along line 11—11 of FIG. 1.

The broken lines depict environmental subject matter only and form no part of the claimed design.
